UNITED STATES PATENT OFFICE.

THOMAS J. McLAUGHLIN, OF CHICAGO, ILLINOIS.

SMOKE-CONSUMER.

SPECIFICATION forming part of Letters Patent No. 293,765, dated February 19, 1884.

Application filed November 19, 1883. (No model.)

To all whom it may concern:

Be it known that I, THOMAS J. McLAUGHLIN, residing at Chicago, in the county of Cook and State of Illinois, and a citizen of the United States, have invented certain new and useful Improvements in Smoke-Consumers, of which the following is a full description, reference being had to the accompanying drawings, in which—

10 Figure 1 is a vertical section of the front part of an ordinary locomotive-boiler. Fig. 2 is a plan view, with the portion above the grate and water-chamber broken away. Fig. 3 is a plan view of the smoke-consuming device; Figs. 4 and 5, details; and Fig. 6, a side elevation of the smoke-consuming device, with the box or case of the superheater in section.

15 The object of my invention relates to an improved construction and operation of the devices used for consuming the smoke, or for preventing its formation in a visible form; and its nature consists in the several parts and combinations of parts hereinafter described and claimed as new.

20 In the drawings, A indicates a boiler; B, the furnace or fire-chamber; C, the grate-bars; D, the feed-door; a b, the inclosing-case for the superheater; c, pipe leading to steam-space or steam-dome; d, steam-pipe leading to coil or superheater; d', the coil or superheater; e e', discharge-pipe; f, discharge-nozzles; g, supporting-frames for the superheating-coil; h, regulating-valve; i, blow-off valve; j, air-vent through the feed-door; k, hinged or sliding door for regulating the admission of air through the opening or openings j; l, ears for attaching the case a.

25 I have shown my device applied to an ordinary locomotive-boiler; but I propose to apply it to coal-burning boiler-furnaces, or fire-boxes of boilers or steam-generators of the various constructions which are adapted to receive it, in the form shown, or in such modified form as does not affect its construction and operation in respect to any of the parts or combinations hereinafter claimed as new.

30 As various forms are well known, a further description of the furnace or fire-box will not be necessary.

35 The superheating coil or bends of my device I usually place in a box or case, a, which is made by furnishing the end plate, b, with

suitable openings or passages for the pipe and placing it in position before building up the coil. When the coil is built up, the case a is 55 slipped over it, and the two parts are fastened together by suitable bolts, as shown at Fig. 6. The case is attached to the wall of the furnace by means of lugs or ears l, through which attaching-bolts are passed, the bolts being 60 simply tapped in when the furnace is made of iron, and when it is made of masonry the bolts are provided with screws and nuts at their outer ends and bolts in the wall. The case is then placed on them and the nuts 65 screwed down.

The number of coils or pipes d' may be varied according to the size and to the intensity of the heat to which they are to be exposed. The number shown will ordinarily be sufficient. 70 These coils are put together by the use of ordinary steam-fittings. The pipe d is usually extended through the front wall, so as to bring the regulating or blow-off valves into position for convenient use. The pipe c is connected 75 with this pipe by an ordinary coupling, and is extended upward, so as to take steam from the steam chamber or dome, and the flow or amount of steam is regulated by the valve h, which valve is of ordinary construction. The end of 80 the coil or superheater is connected with a double pipe, e e', which extends across the front of the furnace or fire space, and usually above the door, as shown. The inner pipe, e', is usually of the same size as the superheating 85 coil, and it is provided with screw-threaded holes along its length, into which the nozzles f are screwed. The pipe e is placed over or around the pipe e', so as to leave a space between them, as shown in Fig. 5. This outer 90 pipe or case is provided with holes, through which the nozzles pass, and the nozzles are screwed in after the two pipes e e' are properly put together. The pipe e is held in position by the nozzles, by the steam-fitting at 95 one end, and the screw-cap shown in Fig. 3 at the opposite end. This outer pipe or jacket prevents the burning out of the steam-pipe and the burning out of the nozzles, as they are very liable to be burned out where they 100 are screwed into the pipe. The nozzles f are small tubes which have their outer ends flattened, as shown in Fig. 4. I usually place them about four inches apart; but this distance

may be varied according as the nozzles have greater or less capacity. The case *a* prevents the superheater or coil from being burned out, and as there is usually a slight leakage of steam from the packings there will be sufficient steam inside of the case *a* to prevent it from being burned out, as I have found by actual use.

I do not limit the use of my superheater in discharge-pipes to their combination with the case *a*, as in some furnaces the case may be omitted; but in ordinary furnaces, and especially in those made of iron, which are subjected to a high heat, its use will be found beneficial, both for the durability and operation of the superheater.

As an additional amount of air is sometimes necessary or beneficial, I have provided the feed-doors *D* with openings or passages *j*. These passages are covered, as shown, by a hinged door or lid, *k*, which is raised or lowered on its hinges to regulate the amount of air admitted at this point; but it is evident that a sliding door with registered perforations may be used in the place of the hinged door shown; and it is further evident that these passages for admitting air may be placed above or below the door; but I prefer to put them in the door, as they do not interfere with any other arrangement when so located, and they are easily cleaned in case of fouling, as the ends can be readily reached when they are applied to the door.

In operation, after the fire has been properly started, the valve *h* is turned to let on the proper amount of steam, and the steam, mingling with the oxygen and hydrogen in the air of the flame-chamber, causes complete combustion of such combustible gases as may improperly pass off, and sufficient oxygen is furnished

to complete the combustion of such particles of carbon as would otherwise pass off unconsumed, or as carbonic oxide. My device thus prevents the formation of visible smoke, rather than consuming it after it is formed, it being well understood that the escaping combustible gases and carbonic oxide cannot be burned after the temperature has been reduced to a very slight extent from any cause.

By a little attention on the part of the engineer or fireman in adjusting the amount of air passing through the openings *j* and the steam passing through the nozzles *f*, perfect combustion can be maintained within the flame-chamber above the fuel, the amount of steam required or used being greater when the fuel is incandescent, while less steam and more air produces better results when fresh fuel is first applied.

What I claim as new, and desire to secure by Letters Patent, is—

1. The pipe or tube *c'*, having two or more discharge-nozzles, *f*, in combination with the case *a*, and a steam-coil, *d'*, forming the superheater, located in the interior of the fire-box, substantially as described.

2. The combination of the coil or superheater *d'*, casing *a*, located in the interior of the fire-box, discharge-pipe *c'c'*, and nozzles *f*, substantially as described.

3. The combination of the pipes *c'd* and valve *h* with the superheating-coil *d'*, casing *a*, inclosing the coil and located in the interior of the fire-box, delivery-pipe *c'c'*, and nozzles *f*, substantially as described.

THOMAS J. McLAUGHLIN.
